UNITED STATES PATENT OFFICE.

ARTHUR HIRSH, OF CHICAGO, ILLINOIS.

UPHOLSTERY-SPRING SUPPORT.

SPECIFICATION forming part of Letters Patent No. 748,073, dated December 29, 1903.

Application filed March 27, 1902. Serial No. 100,278. (No model.)

To all whom it may concern:

Be it known that I, ARTHUR HIRSH, a resident of Chicago, in the county of Cook and State of Illinois, have invented certain new 5 and useful Improvements in Upholstery-Spring Supports, of which the following is a specification.

This invention relates to improvements in upholsterty-spring supports, and refers more 10 specifically to an improved substructure formed of intersecting wires and including improved means for uniting the springs with the substructure.

The salient object of the invention is to 15 provide a simple, highly-efficient, and cheap construction, in which the lower supporting-frame is composed of intersecting wires which are rigidly united with each other, and the upholsterty-spring with both, by means of a 20 simple cheap metal clip.

The invention consists in the matters hereinafter described, and more particularly pointed out in the appended claims, and will be more readily understood from the following 25 description by reference to the accompanying drawings, forming a part thereof, and in which—

Figure 1 is a view, partly in transverse vertical section and partly in side elevation, of 30 the lower end portion of an upholsterty-spring and the supporting-frames to which it is attached. Fig. 2 is a plan view of the supporting-frame with the spring removed, and Fig. 3 is a perspective view of the attaching-clip.

Referring to said figures, 1 and 2 designate 35 a pair of supporting wires or rods arranged in intersecting relation and forming the sub-frame proper, upon which the upholsterty-springs are supported. 3 designates as a 40 whole the lower end portion of an upholsterty-spring interengaged with the supporting-frame, and 4 the sheet-metal clip, whereby the attachment or securing together of the parts is effected.

The supporting-clip 4 comprises, essentially, a base portion 5, which forms a support against which the end of the spring may act, and eye portions connected with said base and extending outside of the plane of 50 the latter, in this instance formed by a circumferential flange 6 and through which are formed retaining eyes or apertures 7 and 7'.

The base of the clip is likewise provided with an aperture 8, which receives a deflected or U-shaped loop portion 1', formed in the cross-wire 1. In the particular embodiment of my invention shown herein the base of the clip is arranged to overlie the main cross-wire 1, and the loop of the latter is accordingly extended upwardly through the aperture 8, 60 while the cross-wire 2 is inserted at right angles to the cross-wire 1 through the eyes 7 and 7' of the clip and under or in engagement with the loop 1', the vertical height or length of the loop 1' and the location of the holding-eyes 7 and 65 7' being such that when the parts are interengaged, as described, the cross-wires will be held in firm bearing with each other at their points of intersection and the base in firm bearing with the underlying cross-wire. 70 The location of the eyes 7 and 7' is sufficiently above the upper surface of the base-plate 5 to admit of passing the lower coil 3' of the spring thereunder, as shown clearly in Fig. 1, while the diameter of the clip or the distance between the flange portions thereof containing the eyes is such that when the coil of the spring is engaged therewith movement of the spring in the direction of the length of the straight cross-wire 2 is prevented. Preferably, and as shown herein, the eyes 7 are located above the base-plate a distance approximating but somewhat less than twice the diameter of the wire of the coil, so that when the coil has been threaded underneath 85 the cross-wire 2 to an extent approximately equal to one revolution its extreme end 3' passes into wedged engagement with the upper surface of the base-plate and the overlying portion of the coil which directly engages the cross-wire 2, thereby causing the spring to pass into a firmly locked or wedging engagement. The pitch or inclination of the coil of the spring and its natural resiliency causes the lower coil to press upwardly 90 against the cross-wire 2 and downwardly against the base portion of the clip, so that all of the parts are absolutely locked or clamped together when the parts are in assembled relation, and owing to the peculiar wedging of the extreme end of the coil underneath the overlying coil, as hereinabove described, the spring in being rotated into engagement with the clip reaches a position 95

where it becomes positively locked against further rotation. The result is that the clip and interengaging eyes of the latter and loop 1' may be so constructed that the parts may 5 be loosely placed together, but nevertheless be held absolutely rigid with each other when the spring is interengaged in the manner described. It will be obvious that disengagement of the parts may be accomplished with 10 the greatest facility by simply rotating the spring in the reverse direction, applying sufficient force to release the wedged engagement hereinbefore described. It is also to be noted that the parts are not only held in rigid 15 relation to each other, but the spring is positively supported upon a circular base, and the lower coil is fastened firmly against the base by the overlying cross-wire, so that the spring is held absolutely rigid against tilting 20 movement in any direction.

It will be obvious that the construction is an extremely inexpensive one, quickly and conveniently assembled, and, further, that the supporting-wires are practically devoid 25 of longitudinal elasticity or stretching capacity, one of them being entirely straight and the other having its loop portions engaged with the clip-aperture in such manner as to prevent any longitudinal elasticity 30 which might be due to the provision of the loops or bends in the wire.

It will be obvious that the details of construction may be modified without departing 35 from the principle of the invention, and I do not, therefore, limit myself to the details shown, except to the extent that they are made the subject of specific claims.

I claim as my invention—

1. The combination with a coiled upholstery-spring, and intersecting supporting-wires, of means uniting said parts comprising a clip having a horizontally-disposed base portion, an eye flange portion upon the base portion, and one or more eye-apertures formed 40 through said flange portion in a plane outside of the plane of the base, one of said united members being threaded through the eye flange portion of the clip and locking the parts together.

2. In combination with a coiled upholstery-spring, and intersecting supporting-wires, means uniting said parts comprising a clip having a base portion and a relatively elevated portion through which latter are formed 5 a plurality of eyes, said eyes being located in a plane substantially parallel with, but removed from the plane of the base, one of said united members being threaded through said eyes and the lower end of the spring being 60 interwoven with the supporting-wires whereby the parts are locked in clamping engagement.

3. In combination with a coiled upholstery-spring, intersecting supporting-wires and a 65 clip uniting said parts comprising a circular base portion upon which the spring rests, a relatively elevated portion, and a pair of dia-

metrically opposite eyes formed through said elevated portion, substantially parallel with but above the plane of the base, one of said 70 intersecting wires being passed through said eyes and above the portion of the spring.

4. In combination with a coiled upholstery-spring, intersecting supporting-wires, one of which is provided with a bend to confine the 75 opposite wire at their points of intersection, and a clip uniting said parts, comprising a circular base member above which the end of the spring is located; a recess in the central portion of said base into which the deflected 80 portion of the bent wire extends and a pair of eyes formed through the clip transversely opposite the recess which receives the bend of the wire through which the intersecting wire extends, for the purposes set forth. 85

5. In combination with a coiled upholstery-spring, and intersecting supporting-wires one of which is provided with a bend to partially embrace the intersecting cross-wire, means 90 uniting said parts comprising a circular base member provided with a central recess to receive the bend of the bent wire, upstanding eye portions diametrically opposite each other and eyes formed through said eye portions, said eyes being located above the upper surface of the base a distance greater than the thickness of the wire of the spring whereby the coil of the latter may be passed between the base and the wire inserted through said eyes. 95

6. In combination with a coiled upholstery-spring and intersecting supporting-wires, means for uniting said parts comprising a metal clip, provided with a base portion adapted to lie in a substantially horizontal plane 100 and having eye portions arranged outside of the plane of the base provided with transverse eye-apertures, one of said supporting-wires being threaded through eyes of the clip and the spring being interwoven therewith, 105 whereby said parts are firmly locked together for the purpose set forth.

7. In combination, a coiled upholstery-spring, a supporting-wire provided with an upwardly-deflected bend intermediate its 115 length and means uniting said parts comprising a clip having a base portion lying upon the supporting-wire and an aperture formed through said base portion through which the deflected portion of the supporting-wire is 120 extended, and means interlocking the end of the spring with the portion of the wire exposed through said aperture whereby the base portion of the clip is clamped between the spring and supporting-wire. 125

8. In combination a coiled upholstery-spring, a supporting-wire and means uniting said parts comprising a clip having a flattened, horizontally-disposed base portion arranged to rest against the supporting-wire, 130 an aperture formed through the base portion of said clip and exposing the supporting-wire therethrough, and means interlocking the end of the supporting-spring with the support-

ing-wire through said aperture of the clip, for the purpose set forth.

9. In combination, a coiled upholstery-spring, a supporting-wire, and means uniting said parts, comprising a clip provided with a base portion arranged to rest against the supporting-wire, and an opening therein through which said supporting-wire is ex-

posed; laterally-disposed, horizontally-extended portions across which a part of the spring is arranged to extend, and means holding said parts in clamping engagement.

ARTHUR HIRSH.
